UNITED STATES PATENT OFFICE.

JOHN H. AYRES, OF PAOLA, KANSAS.

SNOW-PLOW.

SPECIFICATION forming part of Letters Patent No. 244,784, dated July 26, 1881.

Application filed May 2, 1881. (No model.)

To all whom it may concern:

Be it known that I, JOHN H. AYRES, of Paola, in the county of Miami and State of Kansas, have invented certain new and useful Improvements in Snow-Plows; and I do hereby declare the following to be a full, clear, and exact description of the invention, such as will enable others skilled in the art to which it pertains to make and use it, reference being had to the accompanying drawings, which form part of this specification.

My invention relates to an improvement in snow-plows, the object of the same being to provide a device capable of taking the snow from a railroad-track and from the sides thereof, elevating the same, and discharging it from the machine on both sides at right angles to the elevators; and with these ends in view my invention consists in certain details in construction and combinations of parts, as will be more fully explained, and pointed out in the claims.

In the accompanying drawings, Figure 1 is a plan view of my improved device. Fig. 2 is a side view of the same, and Fig. 3 is a transverse section.

A represents a suitable frame, preferably constructed of sheet metal, mounted on the axles B B', carrying the wheels C. D is a rearwardly-inclined platform or apron, situated on the front of the frame, over which the endless conveyers move. This apron is curved or scoop-shaped at the lower end, and is adapted to run slightly above the rail and cut the snow in advance of the elevators, and is also provided with two side pieces, a, and two partitions, e, the latter affording bearings for the shafts carrying the endless elevator, and also for part of the gearing which operates said endless elevator. The two partitions and side pieces above referred to divide the apron D into three compartments, through which pass the shafts c, having grooved-faced rollers c³ journaled therein, and the shaft c' carrying the driving-gear and pulleys, the latter having teeth on their surfaces which engage with the under side of the belts and carry them upward. The side pieces, a, are provided with cutting-edges a', which divide the snow, and the partitions are covered with bridges e', having inclined sides which completely cover the inner

edges of the elevator-belts and prevent the snow from getting under the belts and on the gearing confined therein. The bridges e' are also provided with cutting or dividing surfaces, which operate to direct the snow onto the large or central conveyer, d², and the small side conveyers, d'. The endless conveyers consist of a suitable belt, of any material suited for the purpose, having the shovels d³ riveted or secured thereon in any suitable manner, on which the snow is carried to the top of the same, where it is dropped onto the horizontal conveyers situated behind and below the front elevator. The horizontal conveyers D' wind around the drums or pulleys journaled in the frame in opposite directions, the latter being constructed precisely like those described for the front elevator, and discharge the snow at both sides of the machine with enough force to clear the top of the banks and drifts, which prevents its return onto the track. The frame A is continued upward at the back, which, in conjunction with the wings e², form the rear side of the horizontal conveyers, the front side of which is shorter than the rear side, being formed by the pieces c², situated at the rear of the front conveyers. The space between the adjacent ends of the horizontal elevators is covered by the bridge, having inclined sides, adapted to deflect the snow as it falls from the front elevator onto the horizontal elevators, from whence it is discharged.

B' is the rear axles, to the outer ends of which the wheels C are secured. These wheels are situated to the outside of the frame, and are partly inclosed in separate compartments, which protect them from the snow. Cog-wheels f are rigidly secured to this rear axle inside of the frame A, and mesh with the wheels g loosely journaled on the shaft g', which in turn mesh with cogs h on shaft h', the latter having a bevel-gear wheel rigidly secured thereto, which turns the drums carrying the horizontal elevators. The cogs g, above described, have the sleeves g² secured thereto, with which spring-pressed levers H engage, the latter having the tendency to keep the cogs in engagement with the wheels above and below.

When it is desired to move the machine forward or backward without operating the conveyers, the wheels g are thrown out of engage-

ment and retained by securing the levers H in any desired manner.

The axle B is secured to a bolster, which allows the machine to be easily turned when on ordinary roads. The front axle, B, is rigidly secured in the frame, and is provided with the wheel C, the latter being incased precisely like the rear wheels. Cog-wheels l are secured to this axle B inside of the frame, and mesh with the wheels m loosely journaled on shaft m', the said wheels being provided with sleeves and spring-pressed levers like those described for the rear train of wheels for throwing them into and out of gear. This loosely-journaled wheel m meshes with the wheel o, which meshes with the wheel o' rigidly secured to the drive-shaft c' of the front elevator, and drives the same.

M is a door situated at the rear of the machine, which affords entrance to the interior for oiling the wheels and for operating the spring-pressed levers for throwing the wheels in and out of gearing. The front elevator is of greater width than those ordinarily constructed, and by dividing it into three separate compartments the strain from one side of the conveyer, striking a drift, is not imparted to the other side, and it consequently remains unaffected, and it also cleans the snow more effectually from the outside track when the train is turning short curves than can be accomplished with machines carrying only one elevator-belt. The weight of the machine also produces sufficient friction to run the elevators independently of any connection with the locomotive; but, if desired, I can connect suitable pitmen from the engine with cranks on the front and rear axles to operate the elevators. In the latter case the wheels on the axles could be journaled on a separate shaft, which would allow the rear axle to be constructed to turn without throwing the elevating mechanism out of gear.

If necessary, I can attach the machine to the front of the cow-catcher of the engine; but I prefer to remove the latter, so as to give a solid bearing to the back of the machine, which will cause the latter to run smoothly, and will prevent the jarring and probable damaging of the same when a drift is struck.

When deep drifts are anticipated, instead of using the horizontal elevators to carry the snow off the machine at both sides, one or more horizontal conveyers may be provided to carry the snow backward and discharge it into a car attached to the train for that purpose, and by running into the drifts and backing out and discharging the snow from the receiving-car several times a clearing may be made through drifts which have heretofore been impassable. By using iron or chain belts all the tendency to give will be overcome, and the belts can be tightened or loosened by screws

situated in the upper part of the frame. By coupling the axles by a drive-chain the power 65 can be increased to drive the belts when heavy snows are encountered.

I am aware that snow-plows have been provided with two endless elevators, located respectively on opposite sides of the center of the inclined platform, and snow-deflectors being located in the space between the elevators for deflecting and discharging the snow at opposite sides of the track; also, that two such elevators have been employed in connection 75 with a rotating cutting-wheel; and hence I make no claim to such construction and combination of parts.

In my improved snow-plow I employ a wide endless belt, which is nearly as wide as the 80 track, and which serves to elevate the greater portion of the snow. On opposite sides of the wide central elevator are located narrow side elevators, which extend outwardly from the sides of the track. When the plow is running 85 around curves in either direction, and drifts are encountered close to one side of the track or upon one of the rails, the strain and labor of clearing the snow and elevating it are imposed on one of the narrow elevators, leaving 90 the wide and other narrow elevator free from the lateral or diagonal strain, and thus preventing the shovels from becoming detached or torn from the belts. By the employment of the inclined bridges the ends of the shovels 95 are completely protected and snow prevented from getting between the driving-gear and belts.

Having fully described my invention, what I claim as new, and desire to secure by Letters Patent, is—

1. In a snow-plow, the combination, with the wide central endless conveyer, d², and narrow side endless conveyers, d' d', of the bridges e' e', constructed with inclined sides and arranged 105 to overlap the adjacent edges of the three endless conveyers, substantially as set forth.

2. In a snow-plow, the combination, with the central conveyer, d², and side conveyers, d' d', of the bridges e' e', provided with front cutting-edges, a', said bridges being constructed and arranged to overlap the adjacent edges of the three endless conveyers, substantially as set forth.

3. In a snow-plow, the combination, with the central conveyer, d², side conveyers, d' d', and bridges e' e', of the lateral conveyers D' D', substantially as set forth.

In testimony that I claim the foregoing I have hereunto set my hand this 11th day of April, 120 1881.

JOHN H. AYRES.
